US00D726142S

(12) **United States Design Patent**
Itoh et al.

(10) **Patent No.:** **US D726,142 S**
(45) **Date of Patent:** **** Apr. 7, 2015**

(54) **RADIO RECEIVER**

(71) Applicant: **Hitachi Koki Co., Ltd.**, Minato-ku, Tokyo (JP)

(72) Inventors: **Takafumi Itoh**, Hitachinaka (JP); **Rui Akiba**, Hitachinaka (JP); **Masanori Okada**, Hitachinaka (JP); **Masato Sakai**, Hitachinaka (JP)

(73) Assignee: **Hitachi Koki Co., Ltd.**, Minato-Ku, Tokyo (JP)

(**) Term: **14 Years**

(21) Appl. No.: **29/477,320**

(22) Filed: **Dec. 20, 2013**

(30) **Foreign Application Priority Data**

Jun. 21, 2013 (JP) 2013-014081
Dec. 3, 2013 (JP) 2013-028336

(57) **CLAIM**

The ornamental design for radio receiver, as shown and described.

DESCRIPTION

FIG. 1 is a perspective view of the radio receiver showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof; and,

FIG. 8 is a perspective view thereof showing a cover opened state.

The broken line showing in FIG. 8 is for environmental purposes only and form no part of the claimed design.

1 Claim, 8 Drawing Sheets
